UNITED STATES PATENT OFFICE.

SIMON W. WARDWELL, OF PROVIDENCE, RHODE ISLAND; CARL V. J. CHRISTENSEN, EDWIN C. SMITH, ARTHUR A. ARMINGTON, AND WILLARD W. BARDSLEY EXECUTORS OF SAID SIMON W. WARDWELL, DECEASED.

BOBBIN WINDER.

Application filed April 30, 1919. Serial No. 293,589.

To all whom it may concern:

Be it known that I, SIMON W. WARDWELL, a citizen of the United States, residing at Providence, in the county of Providence, 5 State of Rhode Island, have invented certain new and useful Improvements in Bobbin Winders, of which the following is a specification.

My invention relates to improvements in 10 winding machines and particularly to machines for winding relatively small bobbins and cops for sewing-machines or loom-shuttles. The object of my improvement is to provide an extremely light, simple and easy- 15 running mechanism which may be incorporated in the structure of the sewing-machine head or adapted for attachment to the loom frame. A further object of the improvement is to provide a machine for 20 winding bobbins by a systematic method of disposing the coils in place to secure what is now known in the art as the Wardwell or V-wind, whereby the bobbin or cop is made more compact, and whereof the thread or 25 yarn will deliver more freely with a uniform tension in unwinding it.

The manner and means for carrying out 30 these improvements are fully described in the following specification, illustrated by the accompanying drawings, in which like reference characters designate like parts. In the drawings:

Fig. 1 is a vertical sectional view of a portion of the arm of a sewing-machine head, showing my improved winding-mechanism as applied thereto and illustrating the manually-controlled means for connecting it to be driven from the main drive-shaft of the machine.

Fig. 2 is a vertical sectional view taken 40 on the line X—X of Fig. 1, looking in the direction indicated by the arrow *x*, and showing that portion of the arm which encloses the winding-mechanism and its driving-means;

Fig. 3 is a detail view of the driving-means;

Fig. 4 is an enlarged detail view of the traverse-cam which reciprocates the thread-guide of the winder; and

Fig. 5 is a correspondingly-enlarged perspective view of the thread-guide.

Referring first to Fig. 1, my improved

winder *W* is here shown as incorporated in the head of a sewing-machine, the standard 55 or butt end of the overhanging arm *A* of which serves as a housing and frame for the winding-mechanism. The shell *2* of the arm *A* is cored out at its upper, rearward end to provide a chamber or pocket *3* having 60 walls formed with bearings for the operating elements of the winder. These latter comprise, essentially, a vertical winding-spindle *4*, on which the bobbin *B* is wound, and a reciprocating thread-guide *5* for 65 traversing the thread back and forth on the bobbin. Preferably, the shell *2* of the arm *A* is constructed in two complementary parts with its opposite halves joined in a vertical plane, as indicated at 6—6 Fig. 2, and secured together by suitable cross-pins or 70 rivets 7—7.

The lower end of the winding-spindle *4* is stepped in a bearing *8* in a horizontal web 9 on the interior of the arm *A*, while its 75 upper end *10* projects through a bearing *11* in the shell *2*. The projecting end *10* of the spindle *4* is axially counterbored at *12* and split diametrically at *13* to provide for its contraction when the bobbin-shell *b* is 80 slipped on over it, whereby to cause the spindle to grip the bore of the bobbin to hold it rotatively thereon. For sewing-machine use the bobbin-shell *b* is usually constructed of sheet-metal with a hollow barrel *15* and 85 disk-like end flanges or heads *16—16*; but for loom-shuttle cops or other types of bobbins a paper tube might be used in its stead. Below the spindle-bearing *11* is another bearing *18* projecting inwardly from the 90 shell *2*, and between this and the lower bearing *8* is a tubular sleeve or bushing *19* enclosing the spindle *4* and free rotatively thereof. The sleeve *19* carries the traverse-cam *20* which, as shown more particularly 95 in Fig. 4, is constructed of sheet-metal with a tubular hub *21* supporting the distorted disk *22* at one end. The disk or flange *22* is dished on opposite sides and pressed into shape to form its outer portion with a continuous helical rim *23* arranged in a plane at right-angles to its axis. The hub *21* of the cam *20* is connected rotatively with the spindle-sleeve *19* by means of a pin *24*, the sleeve serving as the driving-element for the 100 cam through means as later described.

As shown in Fig. 5, the thread-guide 5, consists of a relatively thin, flat bar, preferably stamped out from sheet-metal and formed with a rounded, upper end having 5 an inclined slot 25 cut into its side to provide a hook for receiving the thread to be wound. The guide 5 is arranged in parallel relation with the winding spindle 4, see Fig. 1, and slides in slotted bearings 26—27 in the 10 walls of the shell 2. Adjacent its lower end the stock of the guide is punched out to form two integral lugs or ears 28—28 projecting at right angles to its face and bent into opposite V-shape to adapt them to straddle 15 the sides of the rim 23 of the cam 20, see Fig. 4. The upper, slotted end of the guide 5 projects through its bearing 26 in the shell 2 in proximity with the rim of the bobbin 6 and is reciprocated in relation thereto by 20 the rotating traverse-cam 20 which engages its lugs 28—28.

The cam 20 is driven from a gear 30 formed with a hub 31 keyed to the sleeve 20 by means of a pin 32. Beneath the gear 25 30 is another gear 33 having its hub 34 keyed to the spindle 4 by a cross-pin 35. The gear 33 is arranged between the end of the sleeve 19 and the bearing 8, whereby 30 it prevents end movement of the sleeve, besides taking the end thrust of the spindle 4 for which it serves as the driving element. The gears 30 and 33 are connected to be driven from a vertical stud-shaft 36 journaled in a bearing 37 in the wall 9, and 35 a second bearing 38 formed by a cross-rib 39 extending between the sides of the shell 2, see also Fig. 2. The upper end of the shaft 36 is formed with teeth to provide a pinion 40 meshing with the gear 30, while 40 a second pinion 41 has its hub secured to the shaft by a cross pin 42 and is arranged in mesh with the gear 33. The pinion 40 is of less diameter than the pinion 41 so that driving through the larger gear 30 it 45 rotates the sleeve 19 and cam 20 at a relatively slow speed; while the spindle 4 is driven at a much faster rate through the equal gears 41 and 33. At the lower end of the shaft 36 is a bevel-gear 44 secured thereon by a pin 45 extending through its hub 46. The hubs of the two gears 41 and 44 bear 50 respectively against the bearings 37 and 38 to take the end thrust of the shaft 36.

The complete winding-mechanism is embodied in the simple arrangement of parts above described and is operated from the main driving-means of the sewing-machine as next explained: Journaled in bearings 48—49 formed on the interior of the arm 55 A is a horizontal shaft 50 which carries a hand-wheel H at its outer end. In some instances the shaft 50 may serve as the main power-shaft of the sewing-machine, the wheel H being connected to the treadle- 60 operated driving-wheel by a belt, or in 65

other cases driven from the friction gear or an electric motor. In the present embodiment, however, I have shown the shaft 50 as adapted to be driven from a vertical power-shaft 52 through a system of gearing and manually-controlled clutch-devices arranged as follows: The greater portion of the shaft 50 is reduced in diameter and arranged to slide in a bushing 53 which rotates in the outer bearing 49 of the arm 70 A. The hub 51 of the hand-wheel H is secured fast on the bushing 53 by means of pins or keys 54, with its end abutting the end of the bearing 49. Abutting the inner end of the bearing 49 is a bevel-gear 55 secured in place on the bushing 53 by a pin 56 in its hub 57. The gear 55 meshes with a corresponding bevel-gear 58 on the vertical shaft 52 and through this arrangement the bushing 53 is driven continuously 75 therefrom.

On the left-hand end of the shaft 50 is a bevel-gear 60 secured rotatively therewith by a cross-pin 61 in its hub 62; while on the opposite side of the bearing 48 is a 80 similar gear 63 also keyed to the shaft 50 by a pin 64 extending through its hub 65. The hubs 62 and 65 of the gears 60 and 63 are spaced apart on the shaft 50 to allow a limited sliding movement of the shaft in 85 the bearing 48. When the shaft 50 is slid to the left to carry the hub 65 of the gear 63 against the end of the bearing 48 the end gear 60 is carried into mesh with a bevel-gear 66 which is keyed to a vertical 90 shaft 67 by means of a pin 68. The vertical shaft 67 is journaled in bearings 69— 95 70 projecting across the interior of the arm A and at its upper end is a bevel-gear 71 pinned thereto at 72. The gear 71 meshes 100 with a bevel-gear 73 fast on the end of a horizontal shaft 74 which extends to the front of the sewing-machine head and serves to drive the reciprocating needle-bar, not herein shown.

The gear 63 on the shaft 50 is adapted 105 to mesh with the previously-mentioned gear 44 on the lower end of the shaft 36 which drives the bobbin winder W. To engage the gear 63 with the gear 44 the shaft 50 is slid to the right in the bearing 48 and bushing 53, as shown in Fig. 3, and for this purpose a finger-knob 75 is provided on the outer end of the shaft, being fastened thereto by a cross-pin 76, see Fig. 1. The inner end of the knob 75 is formed with radial lugs or teeth 77 adapted to engage slots 78 in the end of the hub 51 of the hand-wheel H to key the shaft 50 thereto, whereby to 110 connect it rotatively with the bushing 53. As shown in Fig. 3, the slots 78 in the hub 51 are notched or offset at their outer ends to provide steps 79 which serve as 115 detents to hold the shaft 50 withdrawn to the right.

Referring to Fig. 1, on the top of the arm A is a spindle 80 held in a lug 81 and adapted to receive the spool S of thread which furnishes the supply to the needle of the sewing-machine. The spool S also supplies the thread for the bobbin B and when the latter is being wound the strand t is led through a tension-device T of any suitable construction, and thence through the slot 25 in the guide 5 to the barrel of the bobbin b.

The method of operation of the bobbin-winder W and the manner of controlling its driving-means is as next explained: Normally, when the sewing-machine is being used for stitching, the control shaft 50 is slid to the left with its end-gear 60 in mesh with the gear 66 on the vertical shaft 67, as illustrated in Fig. 1. It will be noted from this view that when the shaft 50 is in the position above described its gear 63 will be free from the gear 44 on the winder drive-shaft 36 and therefore the winding-mechanism will remain inoperative. When the main power-shaft 52 of the machine is rotated from the treadle or other driving-means its motion is transmitted through the bevel-gears 58 and 55 to rotate the bushing 53. The bushing 53, being connected rotatively with the shaft 50 through its wheel H and the clutch-knob 75, causes the shaft to be driven therefrom and through the gears 60 and 66 drives the vertical shaft 67. The shaft 67, in turn, drives the horizontal shaft 74 which transmits motion to the reciprocating needle-bar; and the under looper-mechanism and feed of the machine may also be connected to be driven from the shaft 67 through suitable connections not herein shown or described.

When it is required to wind a bobbin for the sewing-machine shuttle or looper-bowl the shaft 50 is drawn out to the right and the knob 75 turned slightly to engage the end of its lugs 77 with the offset steps 79 in the slots 78 of the hub 51 of the wheel H. This shifting of the shaft 50 acts to disengage its end-gear 60 from the gear 66 on the shaft 67 so that the parts of the stitching-mechanism connected therewith will remain at rest while the bobbin is being wound. The withdrawal movement of the shaft 50 engages its gear 63 with the gear 44 on the winder drive-shaft 36, while at the same time the knob 75 remains in clutch with the hub 51 of the wheel H so that the shaft 50 is still connected to be driven from the bushing 53, as shown in Fig. 3. Now, when the power-shaft 52 is rotated again the train of gearing 58—55 and 63—44 will drive the shaft 36 to operate the winder W. Referring to Fig. 1, the shaft 36 transmits rotation through the gears 41 and 33 to the winding-spindle 4, and its end-pinion 40 also drives the gear 30 to rotate the

sleeve 19 at a slower rate of speed. Thus, as the spindle 4 is driven at a relatively fast rate to rotate the bobbin b to wind the thread t onto its barrel 15, the cam 20 is also rotated at a slower speed to impart a rising and falling, reciprocating motion to the thread-guide 5. It has before been explained that in preparing the device for winding the thread t is led through the slot 25 in the guide 5 and its end secured to the barrel 15 of the bobbin b, and as the latter is rotated the reciprocation of the guide causes the thread to be traversed back and forth between its heads 16—16. The thread t is thus caused to be laid in helical turns to build up a square-ended cop or bobbin B composed of a regular succession of uniform layers having the windings disposed in closely adjacent turns as illustrated in Fig. 2. When the bobbin is completed the thread from the spool S is detached and again threaded through the needle of the sewing-machine. The winder W is then disconnected from its driving-means by turning and pushing the knob 75 to slide the shaft 50 to the left, whereby the driving-gears 63 and 44 are disengaged and the stitching-mechanism of the sewing-machine once more connected to the drive in the manner as first explained.

It will be observed that my improvement provides an extremely simple, compact winder having its operating-mechanism enclosed within the walls of the sewing-machine head to protect it from dust and lint, while being out of the way and hidden from view so as not to detract from the ornamental appearance of the machine. The parts of the mechanism are few in number and of such design as to provide for constructing them from sheet-metal stampings, whereby to secure the greatest economy in cost of manufacture. It will also be noted that the winding-device proper is arranged to be driven from the power-drive of the machine and actuated at the will of the operator without driving the stitching-mechanism, while being disconectable from the drive through a simple movement of the hand. It is to be understood, however, that my improved winder is adaptable to other purposes than that herein described and may be used as a separate machine or applied to looms and other textile apparatus. Moreover, various modifications might be made in the structure and arrangement of the parts of the mechanism without departing from the spirit or scope of the invention; therefore, without limiting myself to the exact embodiment herein shown and described, what I claim is:

1. In a bobbin-winder for sewing-machines, the combination with the hollow arm of the machine head, of a winding-spindle projecting from bearings in the arm, a

- 44
- thread-guide consisting of a single bar mounted to slide in bearings in the arm and projecting outwardly therefrom in opposite parallel relation to the winding-spindle, a 5 traverse-cam mounted free to turn on the spindle within the arm and engaging directly with the guide to reciprocate the latter, and means within the arm for driving the spindle and cam at different speeds.
- 10 2. In a bobbin-winder for sewing-machines, the combination with the hollow arm of the machine head, of a winding-spindle projecting from bearings in the arm, a dished sheet-metal cam having a helical rim 15 supported from a hub mounted free to rotate on the spindle, a thread-guide consisting of a bar slidable in bearings in the arm and projecting therefrom in parallel relation to the spindle, said thread-guide provided with means integral therewith for engaging opposite sides of the rim of the cam, and means for driving the spindle and cam at different speeds.
3. In a winding machine, the combination 25 with a rotatable winding-spindle, of a helical cam mounted free to rotate on said spindle, a thread-guide slidable in bearings in parallel relation to the spindle and engaging directly with the rim of the cam, a gear 30 fast with the cam, a second gear fast with the spindle, a drive-shaft, and gears fast on said drive-shaft and arranged in mesh with the cam-gear and spindle-gear.
4. In a winding machine, the combination 35 with a winding-spindle on which the cop or bobbin is wound, of a sheet-metal disk-like cam having its rim distorted from the radial plane to form it into a continuous helix, a flat sheet-metal thread-guide provided with 40 a guiding-slot at one end and punched out to form opposite integral lugs for engaging opposite sides of the rim of the cam, said guide slidable in bearings in parallel relation to the spindle, and means for driving 45 the spindle and cam at different speeds.
5. In a winding machine, the combination 50 with a box-like casing, of a winding-spindle journaled in bearings in said casing with its end projecting therethrough to receive the cop or bobbin, a traverse-cam rotatably mounted on the spindle within the casing, a thread-guide slidable in bearings in the casing with its end projecting therethrough and slotted to receive the thread to direct 55 it to the bobbin, said thread-guide formed with integral lugs engaging directly with the cam to cause the guide to be reciprocated therefrom, and means for driving the spindle and cam at different speeds.
- 60 6. The combination with the hollow arm of a sewing-machine head provided with bearings on its interior, of a winding-spindle journaled in the bearings on the arm and projecting through its walls to adapt it to 65 receive the cop or bobbin, a thread-guide 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
- slidable in bearings within the arm and projecting through the walls of the latter in position to guide the thread onto the bobbin, a traverse-cam mounted free to rotate on the spindle and connected directly with the thread-guide to reciprocate the latter, and driving-means enclosed within the arm and adapted to be connected to drive the winding-spindle and traverse-cam.
7. The combination with the hollow arm of a sewing-machine head provided with bearings on its interior, of a winding-spindle journaled in said bearings and projecting outside the arm to receive the cop or bobbin, a thread-guide slidable in bearings on the arm and projecting therefrom in opposite parallel relation to the spindle, a traverse-cam journaled on the spindle within the arm and connected directly with the thread-guide to reciprocate the latter, a main power-shaft extending through the arm, and manually-operable devices for connecting said power-shaft to drive the winding-spindle and traverse-cam.
8. The combination with the hollow arm of a sewing-machine head, of a winding-spindle journaled in bearings on the arm and projecting therefrom to receive the cop or bobbin, a thread-guide slidable in bearings on the arm and projecting therefrom opposite the winding-spindle, a traverse-cam for reciprocating the guide, gearing for rotating the spindle and cam, a shaft for driving the gearing, a power-shaft, a drive-shaft for the stitching-mechanism of the machine, gears on the power-shaft for alternate connection with the drive-shafts of the winding- and stitching-mechanisms, and manually-operable means for shifting said gears.
9. In a sewing-machine bobbin-winder, the combination with a rotatable winding-spindle, of a reciprocable thread-guide arranged opposite the spindle, a traverse-cam for reciprocating the guide, a drive-shaft connected to drive the spindle and traverse-cam, a gear on said shaft, a power-shaft adapted to slide in its bearings, a gear on said power-shaft adapted to be engaged with the gear on the drive-shaft, and means for rotating the power-shaft while allowing it to be slid to shift its gear.
10. In a sewing-machine bobbin-winder, the combination with a rotatable winding-spindle, of a traversing thread-guide, means to traverse the guide, a drive-shaft connected to rotate the winding-spindle and actuate the traverse-means, a gear on said drive-shaft, a power-shaft slidable in its bearings, a gear on the power-shaft adapted to be engaged with the gear on the drive-shaft, a driving-element on the power-shaft, and means for connecting said driving-element rotatively with the power-shaft while allowing the latter to be shifted in relation thereto.

11. In a bobbin-winder, the combination with a rotatable winding-spindle, of a traversing thread-guide, means for traversing the thread-guide opposite the winding-spindle, a drive-shaft connected to drive the winding-spindle and traverse-means, a gear on the drive-shaft, a power shaft slidable in a bushing, a driving-element fast on the

bushing to rotate the latter, means for connecting the power-shaft rotatively with the bushing while allowing it to slide therein, and a gear on the power-shaft adapted to be engaged with the gear on the drive-shaft. 10

In testimony whereof I affix my signature.

SIMON W. WARDWELL.
